UNITED STATES PATENT OFFICE.

THOMAS RODGER, OF DUNEDIN, NEW ZEALAND, ASSIGNOR OF TWO-THIRDS
TO THOMAS BLACK AND ROBERT CRAWFORD, BOTH OF SAME PLACE.

PLOW FOR SPREADING AND TRIMMING BALLAST ON RAILWAYS.

SPECIFICATION forming part of Letters Patent No. 373,907, dated November 29, 1887.

Application filed May 24, 1886. Serial No. 203,133. (No model.) Patented in New Zealand January 6, 1886, No. 1,680.

To all whom it may concern:

Be it known that I, THOMAS RODGER, a subject of the Queen of Great Britain, residing at Dunedin, in the British Colony of New Zealand, engineer, have invented an Improved Plow for Spreading and Trimming Ballast on Railways, for which an application for patent was filed in the British Colony of New Zealand on the 6th day of January, 1886, and numbered 10 1,680; that under the laws governing the grant of patents in said colony the Letters Patent will bear date as of the day of filing; and that up to the present time the patent on said application filed in said colony has not been 15 granted, and of which the following is a specification.

This invention of an improved plow for spreading and trimming ballast on railways is designed to be fixed under a railway-wagon, 20 brake-van, or other railway-vehicle, drawn preferably by the ballast-train, so as to spread and level off the ballast deposited on the line by hopper-wagons to an even and finished surface with a minimum of manual labor. The 25 vehicle carrying my improved plow may, however, be drawn or impelled independently of the ballast-train, if so preferred.

In order that my invention may be well understood, I will now explain it with reference 30 to the attached drawings, in which—

Figure 1 is a side elevation, and Fig. 2 a plan, of the improved plow attached to a brake-van, which is shown in dotted lines in both figures.

35 A is the plow, constructed with a double mold-board, A', to spread the ballast to a sufficient width on each side of the track. It is suspended from the wagon, van, or other vehicle by links or stems B, connected with the 40 screw-nut C and screw C', which together serve to lift it, by the aid of hand-wheel C², clear of the track when traveling and to lower it onto the rails when working. It is also fitted with an additional link or stem, D, which is furnished with a lock-nut, D', and key D² as an 45 additional safeguard for holding the spreading-plow up when traveling, and it is guided and held in its proper position by the guides E, which work in the horn-plates E'.

Its mode of operation when working is to 50 lower it onto the rails and allow it to slide along the top of them, its lower edge being suitably strengthened and shod for the purpose. The lower edge is also shaped so as to spread or plow the surface of the ballast on 55 the track to the cross-section desired, the portion of the spreader between the rails being depressed below rail-level, if desired, with this object.

When traveling, the plow-spreader is lifted 60 up to a sufficient height above the track by the aid of the hand-wheel C² and secured therat.

I prefer to fit the spreading-plow to the last 65 vehicle or brake-van of a train of ballast-wagons constructed according to the specification of an invention entitled "Improved Self-Emptying Hopper-Wagons for Ballasting on Railways," which I am also seeking to patent simultaneously with this invention, although, as before stated, it may be fitted to any other 70 railway-vehicle and drawn or impelled independently of any train.

Having now particularly described and explained the nature of my said invention and in what manner the same is to be performed, 75 I declare that what I claim is—

A ballast spreader and trimmer for use on railways, comprising a plow having a double mold-board, links or hangers connected to said plow for the purpose of suspending the same 80 from a wagon or truck, a vertical screw connected to said hangers and held in suitable supports on the truck, a screw-nut and hand-wheel for rotating said screw and raising and lowering the plow from and to the permanent 85 way, horn-plates secured to the truck, and guides secured to the plow to engage said horn-plates and guide the plow in its vertical movements, a locking-link secured to the plow, and a lock-nut and key engaging therewith to 90 lock the plow in raised position, substantially as set forth.

THOMAS RODGER.
